UNITED STATES PATENT OFFICE.

HARRY N. ALTER, OF CHICAGO, ILLINOIS.

ELECTRIC SWITCH.

1,218,037.

Specification of Letters Patent.

Patented Mar. 6, 1917.

Application filed March 13, 1914, Serial No. 824,515. Renewed January 17, 1917. Serial No. 142,967.

To all whom it may concern:

Be it known that I, HARRY N. ALTER, a citizen of the United States, residing at Chicago, in the county of Cook and State of Illinois, have invented certain new and useful Improvements in Electric Switches, of which the following is a specification.

My invention relates to improvements in electric switches, and in particular to electric switches of the kind known as snap switches. The principal object of my invention is to provide a switch of the kind referred to which will be rugged and economical in construction and convenient and efficient in operation.

Other objects will be set forth and made apparent in the following specification of which the accompanying drawings form a part. In the drawings;

20 Figure 1 shows a side elevation of my improved switch;

Fig. 2 shows a vertical section through the same taken on the line 2—2 of Fig. 3, looking in the direction of the arrow;

25 Fig. 3 shows a top plan view of the same with the cap and other parts removed;

Fig. 4 shows a top plan view of the binding post and contact plate in operative relation to each other;

30 Fig. 5 shows a top plan view of the connecting plate; and

Fig. 6 shows a perspective view of the operating shaft.

Like numerals refer to like parts and elements in the several figures of the drawings, in which the numeral 10 designates an insulating block comprising the base plate 11 and the annular wall 12. The portion 11 has apertures 13 therethrough through which 35 screws or the like may be passed to attach the insulating block to a wall or other structure. Additional holes 14 are provided in the portion 11 through which the electrical conductors are led to the interior of the 40 insulating block. A hub 15 is formed on the upper side of the portion 11 at the center thereof and around said hub are four upwardly inclined arcuate surfaces 16. Each portion having the upwardly inclined surface 16 terminates adjacent the beginning 45 of the next following upwardly inclined surface in a shoulder 16a.

At diametrically opposite points within the insulating block 10 are binding posts 17 carrying the usual clamp screws 18 at their

upper ends by means of which an electrical connection is formed with the electrical conductors which are led in through the apertures 14. Each binding post bears against the inner surface of the wall 12 and has its lower end inturned to seat in a depression 19 formed in the base portion 11 of the insulating block 10 where it is engaged by a screw 20 and held rigidly in position with reference to said block. Each binding post 65 17 forms an electrical connection within the depression 19 with a contact plate 21. These contact plates 21 project inwardly and seat upon two diametrically opposite inclined surfaces 16. An operating shaft 22 is 70 mounted in the hub 15 and retained in position by having its lower end extending through a washer 23, within a depression 24 in the portion 11 of the block 10 where the end of said shaft is riveted. The portion 75 of the shaft 22 immediately above the hub 15 is square in cross section, the shoulders at the lower part thereof bearing on the upper end of the hub 15, and has reciprocably mounted thereon a connecting plate 80 25 which has integrally formed therewith on opposite sides, downwardly inclined arms 26 which have the same curvature as the upwardly inclined surfaces 16 on the portion 11 of the block 10. A coil spring 27 surrounding said shaft, abuts against the upper side of said connecting plate 25 and terminates at its upper end against the under side of a nut 28, which threadedly engages the upper portion 22a of said shaft 22. A cap 29 having the insulating lining 30 is adapted to seat upon the insulating block 10 and has an aperture 31 at the center thereof through which the portion 22a of the shaft 20 projects. A cylindrical head 32 adapted to be 90 engaged by the fingers, carries the internally threaded sleeve 33, by means of which said head is secured to the portion 22a of the shaft 22. The under side of the head 32 is provided with a depression 34 in which is seated a coil spring 35. The other end of the spring 35 bears against a washer 36 which is retained on the sleeve 33 by outwardly turning the outer end of said sleeve. The spring 35 causes the washer 36 to bear 100 against the upper surface of the cap 29 and thereby serves to maintain the cap 29 in fixed position vertically with respect to the block 10 and also to prevent the reciprocation of the shaft 22 in its bearings in case 110

said shaft is not tightly fitted within the hub 15. The cap 29 is provided with a raised portion 29^a which extends around the washer 36 and thereby prevents lateral movement of the cap 29. The upper surface of the wall 12 has mounted thereon a lug 37 which engages a notch 38 in cap 29 and prevents rotation of said cap.

The operation of my device is as follows:

- 10 The parts being in the position shown in Figs. 2 and 3, it is apparent that the connecting member 25, having the arms 26 contacting with the contact plates 21, will form an electrical connection between said 15 plates and the binding posts connected therewith. It being desired to turn off the switch, the head 32 is gripped between the fingers and given a turn through 90° during which movement the connecting member 26 will reciprocate upwardly on the square portion 20 of the shaft 22 until the ends of the arms 26 reach the uppermost points of the shoulders 16^a at which point the spring 27 will cause the member 25 to drop downwardly 25 with the arms 26 adjacent the shoulders 16^b just named, until said arms rest upon the next succeeding pair of inclined insulated surfaces 16, which lie between the contact plates 21. In this position it is apparent 30 that the arms 26 of the connecting member 25 are completely insulated from the contact plates 21, and that the electrical connection is then broken. A backward or anti-clockwise turn of the shaft 22 cannot be made to 35 re-form the electrical connection, because the arms 26 of the connecting member 25 will abut against the vertically extending shoulders 16^a. The electrical connection can be made again only by continuing 40 to turn the shaft in a clockwise direction by means of the head 32, thereby causing the member 25 to again reciprocate on the square portion of the shaft 22 until the arms 26 pass over the next succeeding pair 45 of shoulders 16^a, after which the spring 27 will force the member 25 back into its normal position and cause the arms 26 to again contact with the contact plates 21.

It is thus apparent that the electrical connection between the binding posts is made and broken, alternately by a continuous turning of the switch in the same direction. It is further apparent that my improved switch is constructed of a very small number 50 of parts so that it may be constructed at small cost and may be easily repaired. For instance, if the connecting plate 25 becomes worn or damaged the nut 28 may be readily removed from engagement with the portion 22^a of the shaft and the plate 25 withdrawn from position to be repaired or replaced. If desired, the contact plate 21 and binding post 17 may be made in a single 55 piece, as shown, in which case but three 60 stampings of conducting material will be 65

necessary to form the connecting parts of the structure. It may be desirable, at times, however, to form the binding post 17 and contact plate 21 of separate pieces of material joined together by means of the 70 screw 20.

From the foregoing description, it is apparent that I have described in detail one particular form of my invention, but it is obvious that the principle thereof may be 75 embodied in other structures without departing from the spirit of my invention as embodied in the appended claims.

What I claim is:

1. In a device of the class described, an 80 insulating base having an annular shoulder extending transversely thereto at its outer edge, an integral central hub projecting from said base within said annular shoulder, said hub having a series of arcuate upwardly inclined surfaces formed thereon, each of said arcuate surfaces terminating in a shoulder adjacent the extremity of the adjacent arcuate surface, binding posts secured to said base and extending beyond 85 said annular shoulder, contact plates formed integrally with said binding posts and seated upon alternate diametrically opposite arcuate surfaces of said hub, a shaft rotatably mounted in said hub concentric with 90 said arcuate surfaces, a connecting plate reciprocably and non-rotatably mounted on said shaft and having flexible arcuate arms adapted to contact with said contact plates when the shaft is turned to proper position, a coiled spring mounted on said shaft and arranged to cause the connecting plate to engage said arcuate surfaces; and a cap 95 engaging said shaft and seating upon said annular shoulder.

2. In a device of the class described, a circular insulating base having an integral annular shoulder extending upwardly therefrom at its outer edge, a central hub formed integrally with the base and projecting therefrom within said annular shoulder, whereby an annular channel is formed between the shoulder and hub, said hub having a series of arcuate upwardly inclined surfaces formed thereon each terminating in a shoulder at the extremity of the adjacent arcuate surface, said base having depressions formed in the lower wall of the channel, binding posts having terminals extending upwardly beyond said annular shoulder and having parts seating in said depressions to be engaged by screws passing through said base from the underside thereof, contact plates formed integral with the parts of the binding posts which seat in said depressions, said contact plates being arranged to seat upon alternate diametrically opposite arcuate surfaces, a connecting plate reciprocatingly and non-rotatably mounted 100 on said shaft and having flexible arcuate 105 surfaces.

3. In a device of the class described, a circular insulating base having an integral annular shoulder extending upwardly therefrom at its outer edge, a central hub formed integrally with the base and projecting therefrom within said annular shoulder, whereby an annular channel is formed between the shoulder and hub, said hub having a series of arcuate upwardly inclined surfaces formed thereon each terminating in a shoulder at the extremity of the adjacent arcuate surface, said base having depressions formed in the lower wall of the channel, binding posts having terminals extending upwardly beyond said annular shoulder and having parts seating in said depressions, said contact plates being arranged to seat upon alternate diametrically opposite arcuate surfaces, a connecting plate reciprocatingly and non-rotatably mounted 110 on said shaft and having flexible arcuate 115 surfaces.

4. In a device of the class described, a circular insulating base having an integral annular shoulder extending upwardly therefrom at its outer edge, a central hub formed integrally with the base and projecting therefrom within said annular shoulder, whereby an annular channel is formed between the shoulder and hub, said hub having a series of arcuate upwardly inclined surfaces formed thereon each terminating in a shoulder at the extremity of the adjacent arcuate surface, said base having depressions formed in the lower wall of the channel, binding posts having terminals extending upwardly beyond said annular shoulder and having parts seating in said depressions, said contact plates being arranged to seat upon alternate diametrically opposite arcuate surfaces, a connecting plate reciprocatingly and non-rotatably mounted 120 on said shaft and having flexible arcuate 125 surfaces.

5. In a device of the class described, a circular insulating base having an integral annular shoulder extending upwardly therefrom at its outer edge, a central hub formed integrally with the base and projecting therefrom within said annular shoulder, whereby an annular channel is formed between the shoulder and hub, said hub having a series of arcuate upwardly inclined surfaces formed thereon each terminating in a shoulder at the extremity of the adjacent arcuate surface, said base having depressions formed in the lower wall of the channel, binding posts having terminals extending upwardly beyond said annular shoulder and having parts seating in said depressions, said contact plates being arranged to seat upon alternate diametrically opposite arcuate surfaces, a connecting plate reciprocatingly and non-rotatably mounted 130 on said shaft and having flexible arcuate surfaces.

arms adapted to contact with said contact plates when the shaft is turned to the proper position, a coiled spring mounted on said shaft and arranged to cause said connecting plate to engage said arcuate surfaces, and a cap engaging said shaft and seating upon the upper surface of said annular shoulder.

In testimony whereof, I have subscribed my name.

HARRY N. ALTER.
